James Hart and Waller S. Holladay, Spotsylvania, Virginia

Seth's Patent

The scheme set forth in this Seth's Patent and making part of the same, containing a description in the words of the said James Hart and Waller S. Holladay of their improvement in the construction of the Cylinder and concave of Wheat Threshing Machines.

To all to whom these presents shall come. Be it known that we James Hart and Waller S. Holladay of the County of Spotsylvania and State of Virginia have invented a new and useful improvement in the Construction of the Cylinder and Concave of Wheat Threshing Machines and that the following is an exact description of the Construction and operation of the said Cylinder and Concave as follows, viz.

The axis of the Cylinder is made of a bar of iron one inch and a quarter square and of sufficient length; in a Cylinder of from two to three feet long, the length of the Cylinder depending upon the horse power which is to be applied, in this axis the Cylinder is thus cushioned, Cut bared iron which is from two to three inches wide and from three sixteenths to half an inch thick, into lengths of from sixteen inches to two feet according to the intended diameter of the Cylinder. In the centre of these bars cut a square hole corresponding in size with the size of the axis. Each bar with the hole in it will appear thus

The bar is then put on the axis at the place where the Cylinder commences. This being done a circular piece of plank one inch less in diameter than the length of the bar of iron one inch thick, as may be necessary to keep the bars at the required distance from each other with a hole in the centre of the same size with that in the bar. put in the manner on the axis and project the bars from the head of iron to make them stand more firmly together a groove is cut round the plank corresponding in depth to the thickness of the bars and into this groove the bars will fit. This done

another bar like a key made up of two like Mallets with two uprights
so that it stands at right angles with the first. Then are two pieces
of plank joined like the first. In this manner the whole cylinder is constructed
each successive band being like at right angles with the preceding one. Then
as many bars and circular pieces of plank have been put on as may be
necessary to make the cylinder of the intended height. To bind the whole
cylinder firmly together four rods of iron each half of an inch in diameter
are passed through the cylinder, one end of each rod is bent in the outer side through
one range of the bars, another through another range about three and
a half inches from the bars of the last or an inch and a half from the outer
edge of the circular pieces of plank, holes having been previously made through
each of the last pieces. These are cut at the end of the rods and tapped so
as to be adapted to them. The tops are turned tightly in these holes and
pieces of plank firmly together that the cylinder cannot be broken by any
ordinary force applied to it to prevent any motion of the cylinder in the axis
vertically strong bars are made on the axis against the terminating bar
at each end of the cylinder. The cylinder is fixed in a box framed as the
box of the drawing machine generally are.

The crown is formed in the following
manner. Plank five or six inches wide and of the same thickness with that
used in constructing the cylinder is divided into lengths of about ten feet and
a half. A segment of a circle is then cut out of each piece as represented
in the following figure which give a lateral view of it. The segment begins
rising at A and ending at B.

The iron teeth shown in the representation above given by the figures 123 can
be about six inches long and an inch and a half wide and about three
eighths of an inch thick are then be fitted the plank to a depth corresponding
with their thickness between the points A and B the top of the teeth reaching
about two inches below the surface of the crown. Another plank of exactly
the same size and form is then added over these smaller teeth and let
into it at precisely corresponding points. Thus the whole crown is then
constructed by adding pieces of plank of like size and form each having

ing them on both sides of it as shown above until it has attained the dimensions required. I will all together form iron rods each having one inch in diameter and pass through the plank as through each range of the iron teeth at the distance of about three inches from the iron and another behind each range of the iron teeth and at least by as square in contact with them so as to support them and at the distance of about one inch above the bore holes, for this purpose having been previously made. These holes are represented in the above figures where we cut at both ends of each rod and tops made fitted to them and secured tightly to make the crease as strong as the Cylinder. The crease is the segment of a circle having the centre of the cylinder for its centre. Shoulders are cut at the ends of the planks which form the crease. These shoulders are seen at the letters C and D. The crease is then let down through the frame of the thrashing box to such a depth that the teeth of the crease are then sixteen to of an inch distant from the surface of the cylinder. The shoulders resting on the upper part of the frame of the box to keep it immovable two pieces of timber are laid across it and firmly fixed there by means of iron bolts which pass down through them and the plank of the crease into the frame of the box. The bolts having strong heads at the upper end and screws and tops at the other. The crease being thus fixed and the cylinder put in motion the bars of the latter strike upward passing at the distance of three distances of an inch from the surface of the crease and at the same distance from the teeth on each side. The cylinder is put in motion by means of a reel passing over a block or wheel fixed on the end of its axis. Any time from will do, & regulated as to give from six hundred and fifty to twelve hundred revolutions per minute to the cylinder, one of these wheels requiring more revolutions in a given time than one of greater diameter. The bars of the cylinder and the teeth of the crease are so fixed in the above plan of construction that they cannot fly off and break & thus lose and strength that they cannot be broken by ordinary instruments found in the world.
